F. C. ANDERSON.
SWITCH STAND.
APPLICATION FILED JUNE 10, 1922.

1,427,082.

Patented Aug. 29, 1922.

Fig. 1.

Fig. 6.

A technical drawing of a mechanical assembly, likely a valve or fitting. The drawing shows a central vertical structure with a flange at the top. Various parts are labeled with numbers: 39, 41, 44, 35, 29, 34, 30, 1, 41, 37", 6, 36, and 35. The parts are represented by different hatching patterns and lines, indicating different materials or features. The drawing is oriented vertically, with the flange at the top.

FRANK C. ANDERSON, OF CINCINNATI, OHIO.

SWITCH STAND.

1,427,082.

Specification of Letters Patent. Patented Aug. 29, 1922.

Application filed June 10, 1922. Serial No. 567,386.

To all whom it may concern:

Be it known that I, FRANK C. ANDERSON, a citizen of the United States, residing at Cincinnati, in the county of Hamilton and 5 State of Ohio, have invented certain new and useful Improvements in Switch Stands, of which the following is a specification:

My invention relates to ground-lever parallel-throw switch-stands in general; and in 10 certain respects it relates more particularly to the switch-stands disclosed and claimed in my Patents No. 1,360,862, dated November 30, 1920, No. 1,389,730, dated September 6, 1921, No. 1,407,454, dated February 21, 1922, 15 and No. 1,413,152, dated April 18, 1922.

Its object is to simplify the construction and operation of switch-stands of this character, to effect economy in their maintenance, and, where desirable, as in yard use, to dispense with the use of latches for holding the switch in closed position. Other objects, peculiar to the present invention, as well as in common with those of the mentioned patents, will appear in the course of the ensuing description.

I attain these objects by the device illustrated, for example, in the accompanying drawing, in which—

Figure 1 is a sectional plan view of the 30 switch-stand, the major part of the section being on the plane of the line 1—1 of Fig. 2 through the upper part of the casing, and a minor middle part of the section being on the plane of the line 1'—1' of Fig. 2 through 35 the front shaft bearing;

Fig. 2 is a sectional front elevation, the major part of the section being on the plane of the line 2—2 of Fig. 1 through the middle part of the base and casing, and a minor part, at the middle, being on the plane of the line 2'—2' of Fig. 1 through the front shaft bearing;

Fig. 3 is a vertical front-to-rear section on the plane of the line 3—3 of Fig. 1;

Fig. 4 is a perspective detail of the handle-lever crank;

Fig. 5 is a similar view of the rack or slide;

Fig. 6 is a similar view of the front-bearing bushing;

Fig. 7 is a similar view of the hollow key-pin for the front-bearing bushing; and Fig. 8 is a partial section corresponding to a section in a vertical transverse plane through the center of the target shaft, better 55 showing the connection of the intermediate crank and direct-switch-throwing crank connection, and also showing a modified switch-connecting rod and pin therefor.

The base of the stand comprises the middle 60 part 1 with feet 2 at opposite ends, extending down and being provided with openings through which they are spiked or screwed to the respective cross-ties or head blocks of the switch, not shown. At the opposite ends 65 of the flat middle part 1 are downwardly opening sockets 3 with openings for passage of bolts. This base also comprises the front shaft bearing 4 and the segmental extension 5 at the rear, the latter having the concentric bearing opening 6 in front-to-rear alignment with the front bearing 4. Just to the rear of this front bearing 4 the base has the depression 7; and at opposite ends of the base middle flat part 1 are upstanding pedestals 8, each with an upper transverse opening and a lower transverse opening, receiving the ends of guide-bars 9, which thus extend across the base, above the rear of the depression 7, one above the other, and the 80 lower bar 9 being a considerable distance up from the top of the base middle flat part 1.

The casing comprises the front shaft bearing 10, rear extension with target-shaft-bearing opening 11, and bolt ears 12 at its 85 opposite ends fitting onto the tops of the socket parts 3 of the base when the casing, which has an open bottom, is placed down over the interior working parts assembled on the base, with the casing lower edges fitting 90 closely on the base middle flat part 1 along the edges of the latter. The casing is held down on the base by bolts 13 through ears on the base and casing at opposite sides of the front bearings 4 and 10, and bolts 13' in 95 the base sockets 3 and up through the casing ears 12.

The handle-lever 14 is adapted to be thrown to one side or the other and to rest on one or the other of the lever-rests 14', 100

which it will be understood are spiked or otherwise secured to the ties or head blocks of the switch, not shown. At the free end of this handle-lever 14 is the weight-handle 15 of approved design, and at the other end, preferably forged integral with the handle-lever, is the crank-shaft 16, lying in the front bearings 4 and 10 and extending back over the depression 7.

10 The handle-lever crank 17 comprises a hub 18 fitting on the inner end of the shaft 16 and held thereon by a key-pin 17' and a transverse pin 17", and also comprises a wrist 19 extending rearwardly; and it is 15 radially alined with the lever 14.

The rack or slide member 20 comprises the upper middle part 21 with upper side parts 22 extending rearwardly from its opposite ends, downward projections or teeth 23 at 20 the front, equally spaced from the vertical median line of the member 20, and rear bearing parts 24 extending down from the upper side parts 22 and joined to the projections or teeth 23, and having transverse 25 holes 25 above and below, which fit on the respective guide-bars 9. These guide-bars 9 are held against lengthwise movement in their supporting pedestals 8 by cotters 9' through the bars against the inner sides of 30 the pedestals 8; and the rack or slide member 20 thus is adapted to slide along the bars 9 across the switchstand, as driven by the crank 17 having its wrist 19 engaging between the downward projections or teeth 23 35 of the member 20. The middle of the upper middle part 21 of this member 20 preferably is depressed, as at 26; and along opposite ends of the top of the member, from front to rear, are the upstanding jaws 27, with 40 narrow undepressed parts next to their inner sides at opposite ends of the middle depression 26. These undepressed parts, and the inner sides of the jaws 27, may be finished smooth and straight.

45 The target-shaft 28 will be understood to be of suitable design in its upper part, not shown, to support a target or lamp or other means at any required height; and the intermediate crank 29, of radius suited to the 50 throw of the rack member 20, has the hub 30 receiving the target-shaft 28 down through it. The bearing block 31 is flat, with parallel opposite sides and a central circular opening, and fits slidingly between the jaws 55 27 of the member 20 and down on the undepressed adjacent parts of the top of this member. The arm of the intermediate crank 29 has near its front end the downwardly projecting bearing lug 31' fitting snugly in 60 the central opening of this block 31, over the depressed middle part 26 of the top of the member 20, by which it has ample clearance therefrom; while the target-shaft 28 extends up through and bears in the opening 11 of

the casing, and the lower part of the hub 65 30 extends down into and bears in the base opening 6, with the flange 32 bearing on the base therearound, supporting the crank 29 at the proper height to work easily with the bearing block 31 and rack member 20. Pins 70 33 fix the target-shaft 28 in the crank hub 30.

The direct-switch-throwing crank 34 comprises the hub fitting up in the opening 6, with clutch-teeth 35 engaged in a transverse groove in the bottom of the hub 30, and the target-shaft 28 has its lower end screwed into the center of this hub, thus holding it firmly to the intermediate crank 29. The crank 34 also comprises the opposite radial arms 36 integral with the hub and having 80 openings up and down through them near their outer ends.

As shown in Figs. 1, 2 and 3, the switch-connecting rod 37 simply lies on the top of one of the crank-arms 36, with a pin 38 having a lower reduced part fitting in the crank-arm opening and an upper larger part embraced by the rod 37. At the junction of these parts of the pin 38 it is still more reduced by a groove 38' around it, so that 90 the pin 38 will break before any part of the switch or other part of the switch-stand breaks, in the event of the switch being run through in the wrong direction. This is desirable when the switch-stand is used in 95 yards, where such running through is frequent and the temporary derangement of the installation is more permissible than on main lines, because of the lower speeds, absence of passenger traffic, and more frequent 100 opportunity for inspection of the switches. In the modification shown in Fig. 8, the switch-connecting rod 37' has a fork, the members of which lie above and below the crank-arm 36, and the pin 38", passing down 105 through the rod members and the arm 36, with a head bearing on top of the upper rod member, is not reduced in cross-section as is the pin 38 of the first example, so that 110 it is not liable to break under any ordinary conditions of main-line use, where the high speeds and the danger to life make any breakage of any part highly objectionable.

In this latter example, for main lines, it will be understood that latches, with locks, 115 for the handle lever 14, would replace the simple lever-rests 14' shown in Figs. 1, 2 and 3. In yard use, however, with my present invention, no latch is needed to hold the switch closed, because the crank 17, at either 120 end of its throw of 180°, lies horizontal, or on dead center with respect to the rack or slide 20; so that any force at the switch point-rails, tending to open the switch, is positively resisted by this crank in this position, through the medium of the rack 20, intermediate crank 29, rigidly clutched direct-switch-throwing crank 34 with its integral 125

arms 36, and switch-connecting rod 37 secured by pin 38. My invention thus differs in this respect from those of my prior patents above referred to, which, by a gear-and-rack connection permit the handle-lever 14 to throw over if the switch is run through in the wrong direction; the leverage being such that the handle-weight 15 holds the switch closed under normal traffic without 5 a latch. On account of this positive holding of the switch, as if it were latched, some form of breakable connection, such as the pin 38 with reduction 38', is desirable in the interest of economy and quick repair after the 10 frequent runs through the switch, in yards, as before alluded to.

In main line use, this positive holding of the switch in closed position, by my present invention, is useful in the event of an operative forgetting to latch a main-line switch, or of the latch, together with its lock, being torn away by any object projecting or dragging on a passing train. The handle-weight 15 keeps the lever 14 down to the dead-center 20 position of the crank 17, so that the switch is locked positively whether a latch holds the lever 14 down or not.

The simple pin connection, either with the breakable pin 38 or the non-breakable pin 38'', is permitted by virtue of the rear extensions 39 on the switch-stand base, and the bottom flanges 40 on this base, which prevent the pin of either kind from rising out of place, and prevent the rod 37 in Figs. 1, 2, 30 and 3 from rising off the pin 38. For inserting the pin, the extensions 39 have the slots 41 at mid-position of the crank 34. This combination is disclosed and claimed in my Patent No. 40 1,389,730, before mentioned; being also disclosed in the two later patents mentioned. The bearing block 31 affords a firm, long-wearing, operative connection between the rack 20 and intermediate crank 29; this combination being disclosed and claimed in my 45 Patent No. 1,413,152, before mentioned. The simple crank 17 and two-toothed rack member 20 permits a very economical construction which will wear well, and which 50 will not become deranged easily by excessive wear in the bearings, either of itself or of the other operative parts. Thus, the entire train of connections from the handle-lever 14 to the switch-connecting rod 37 or 37'' is 55 such that excessive lost motion is avoided, even after long use of the apparatus. This, together with its low first cost, makes it desirable for main line use in preference to my prior stands, in which use the automatic 60 throw-over of those stands is not an advantage, since all main line stands must be locked. Also, for yard use, the simplicity and durability, and the ease of repair of the breakable connection, make my present in-

vention preferable, in some cases, to the 65 automatic-throw-over stands of my prior patents; chiefly in view of the compactness, lightness, and consequent low cost of production. The two arms 36 of the crank 34 permit connection for either right or left 70 turn-out switches.

This simple crank and rack combination has an advantage similar to that of my prior inventions in that it affords the switchman a high average leverage in throwing 75 the switch. At the beginning of the throw, when the weight-handle 15 must be lifted directly, the crank wrist 19 is moving almost parallel with the rack teeth 23, so that the ratio of switch movement to the manual 80 movement is very low, with corresponding advantage to the manual effort. As this ratio rises and the advantage diminishes toward the middle of the throw, the weight 15 is more and more supported by the lever 85 14, so that the switchman is relieved of lifting the weight 15 as his mechanical advantage decreases. Likewise, at the end of the throw, the weight 15 has great advantage 90 in overcoming the switch-rail resistance, so that even if the switchman neglects to push the lever entirely down, gravity will complete the switch-throwing. Thus the apparatus is safer, as well as easier to operate, than switch-stands having a uniform ratio 95 in this respect throughout the throw.

Further to insure against lost motion after a long period of use, I prefer to provide in the front shaft bearings 4 and 10 an integral tubular bushing 42, placed on the shaft 16 100 before the crank 17 is placed thereon, and placed in the base bearing 4 along with the handle-lever, shaft and crank assembly, after which the casing with its bearing 10 is placed thereover. This bushing 42 has, mid-way of its length, four holes 43 through its wall, equally spaced therearound. The casing bearing 10 has a hole in its top, at the middle, registering with one of the bushing holes 43 when the bushing 42 is turned 110 with such hole uppermost; and a key-pin 44 fits in the registering holes and prevents turning or endwise movement of the bushing 42 in the bearings 4 and 10. Preferably, this pin 44 is hollow, forming a conduit through which lubricant may be supplied to the bearing of the shaft 16; and to prevent the pin 44 from rising out of its holding position, it has a shoulder 44', above which it is of reduced diameter; and 115 the hole in the bearing 10 is smaller than the bushing holes 43 so that this reduced upper part of the pin 44 fits in it snugly. As shown, the lower or inner side of the casing bearing 10 has a recess 45 with a flat top, 120 up against which the pin shoulder 44' bears, rather than against the concave inner surface of the bearing. By providing four

holes 43 in the bushing 42, it may be turned with any of these uppermost to receive the key-pin 44; thus the bushing may have any one of four positions relative to the shaft 5 16. When the bushing 42 becomes worn in one direction due to prevailing strains in operation, it may be shifted 90° upon removal of the casing; then being held with different surface presented to the shaft 16 10 to resist these prevailing strains, after the casing and the pin 44 are replaced. Also, this bushing may be of more durable material than that of the base and casing. For instance, the base and casing preferably are 15 of gray iron castings, for economy; but the small bushing 42 may be of steel, and may be hardened. However it is not desirable that this bushing be harder than the shaft 16; it being understood that this bushing, 20 after becoming entirely worn, may be replaced by a new one.

This provision for maintaining the bearing of the crank 17 is desirable; but it will be understood that it is not essential. The 25 simplicity of the crank-and-rack combination, in which the rack amounts to a two-tooth rack and the crank to a one-tooth pinion, never unmeshed from the rack teeth even with extreme looseness of the crank-shaft 30 bearing, makes provision for maintaining this bearing even less necessary than with any of the numerous multiple-tooth gearing connections, including my prior inventions referred to herein.

35 Modifications other than those herein exemplified may occur under different conditions. Therefore, while certain constructional details are deemed preferable in connection with my invention, and I have 40 shown and described these rather specifically in elucidating the construction and use of my invention, as is required, I do not wish to be understood as being limited to such precise showing and description, but what 45 I claim as new and desire to secure by Letters Patent is:

1. In a switch-stand, mechanism comprising a lever and a crank coaxially connected in radial alinement, a rack above and engaged by said crank, an intermediate crank operatively related to said rack thereabove, a direct switch-throwing crank coaxially connected with said intermediate crank, and means operatively supporting 55 said mechanism.

2. In a switch-stand, supporting means, a rack element and a lever operatively mounted on said means, a crank coaxially connected to said lever in radial alinement 60 therewith and engaging with said rack, an intermediate crank operatively related to said rack element and having a bearing in said supporting means, and a direct switch-throwing crank coaxially connected with

said intermediate crank and offset downwardly therefrom. 65

3. In a switch-stand, supporting means, mechanism operatively supported by said means, comprising a lever and a crank coaxially connected in radial alinement, a rack element having teeth engaged by said crank, an intermediate crank in operative relation to said rack element, and a direct switch-throwing crank coaxially connected with said intermediate crank and extending 75 below the lowest part of said supporting means for connection to switch-connecting means therebelow.

4. In a switch-stand, mechanism comprising a lever and a crank coaxially connected 80 in radial alinement, a rack engaged by said crank, an intermediate crank operatively related to said rack, a direct switch-throwing crank operatively engaging with said intermediate crank coaxial therewith, and 85 a shaft screwed into said direct switch-throwing crank and non-rotatively fixed in said intermediate crank.

5. In a switch-stand, mechanism comprising a lever and a crank coaxially connected 90 in radial alinement, a rack engaged by said crank, an intermediate crank operatively related to said rack, a direct switch-throwing crank comprising an arm and a hub integrally connected, said hub operatively 95 engaging coaxially with said intermediate crank, and a shaft screwed into said hub and non-rotatively fixed in said intermediate crank.

6. In a switch-stand, a crank on an up-right axis, a direct-switch-throwing crank comprising an arm and a hub integrally connected, said hub operatively engaging coaxially with said first crank, a shaft screwed into said hub and non-rotatively fixed in 105 said intermediate crank, a lever, and an operative connection from said lever to said cranks.

7. In a switch-stand, a base comprising a front-to-rear shaft bearing at its front and a depression to the rear of said bearing, a lever with a shaft in said bearing, a crank fixed on said shaft in radial alinement with said lever and lying within said depression, up-standing means on said base near opposite 110 ends thereof, guide-bars having their ends supported on said up-standing means and extending along said base one above the other near the rear of said depression, a rack member sliding on said guide-bars and having 115 projections on its bottom engaged by said crank, a bearing block guided from front to rear on the upper part of said rack member, a crank turning in said base on an upright axis, to the rear of said depression, pivotally engaging with said bearing block, 120 a direct switch-throwing crank comprising an arm and a hub integrally connected, said 125

- hub operatively engaging coaxially with the crank on the upright axis, a shaft screwed into said hub and non-rotatively fixed in said intermediate crank, an extension on 5 said base overlying said crank arm to retain connecting means therein and having an opening over an intermediate part of the path of travel of said crank arm to admit said connecting means, a bushing around 10 said shaft of said lever in said front shaft bearing, having a plurality of radial openings, and a hollow pin projecting into one of said openings of said bushing and projecting outside said bearing.
- 15 8. In a switch-stand, a lever and a crank coaxially connected in radial alinement, a casing enclosing said crank, and means operatively connecting said crank to a switch whereby said crank is disposed substantially parallel with the direction of 20 initial switch-throwing movement of the operatively connecting means, to hold the switch in closed condition.
9. In a switch-stand, a lever and a crank 25 coaxially connected in radial alinement, a casing enclosing said crank, a rack enclosed in said casing and engaged by said crank, and means extending outside said casing and operatively connecting said rack to a switch whereby said crank is disposed substantially parallel with the direction of 30 movement of said rack to hold the switch in closed condition.
10. In a switch-stand, a lever and a crank 35 coaxially connected in radial alinement, a rack engaged by said crank, an intermediate crank and means to operatively connect said intermediate crank to a switch, and means pivotally engaged by said intermediate crank and slidably engaging said rack.
11. In a switch-stand, a base, a lever and a crank coaxially connected in radial alinement and mounted on said base, a rack engaged by 45 said crank, guiding means, means on said rack slidably embracing said guiding means, and means to operatively connect said rack to a switch.
12. In a switch-stand, a base, a lever and a crank coaxially connected in radial alinement and mounted on said base, a casing enclosing said crank, mechanism enclosed in said casing, comprising a rack engaged by 50 said crank, guiding means, one above the other past the end of said crank where it engages with said rack, and means on said rack slidably embracing said guiding means, and means extending outside said casing to operatively connect said rack to a switch.
- 60 13. In a switch-stand, a base comprising a front-to-rear shaft bearing at its front and a depression to the rear of said bearing, and upstanding means on said base near opposite ends thereof, near the rear of said depression, and having means one above the other for supporting guide-bars, one above the other, across said base.
14. In a switch-stand, a rack member comprising an upper part with parallel jaws on its top, downward extensions near opposite ends of said upper part to receive part of a crank between said extensions, and other downward extensions, joined to the respective first mentioned downward extensions and having openings to receive guiding means for the rack member, one above the other.
15. In a switch-stand, a rack member comprising horizontal and upright parts for slidable engagement of respective operative connections, a slidable block against one of these parts, forming a bearing for the respective operative connection and means for guiding said rack member.
16. In a switch-stand, a rack member comprising pairs of horizontal and upright parts, operative connections engaging between the parts of the respective pairs, a slidable block around one of said connections, forming a bearing therefor, and means for guiding said rack member.
17. In a switch-stand, in combination with a casing, and a lever and a switch-connecting rod outside said casing, three cranks, one inside said casing and connected to said lever and another outside said casing and connected to said rod, and the third crank inside said casing and connected to this other crank coaxially to turn therewith, and a sliding element inside said casing, operatively connecting this third crank to the crank connected to said lever.
18. In a switch-stand, a casing, two cranks on axes disposed at right angles to each other, one inside and the other outside said casing, slidable connecting means inside said casing whereby the one crank turns through substantially twice the angle of the other, and means to operatively connect this other crank to a switch.
19. In a switch-stand, a connected lever and shaft, means operatively connecting said shaft to a switch, a bearing for said shaft, a bushing around said shaft in said bearing, having a plurality of radial openings, and a hollow pin projecting into one of said openings and projecting outside said bearing.
20. In a switch-stand, a connected lever and shaft, means operatively connecting said shaft to a switch, a bearing for said shaft, a bushing around said shaft in said bearing, having a plurality of radial openings, and means engageable in said bearing and engageable in any one of said openings to hold said bushing in various rotated adjustments.
21. In a switch-stand, a connected lever

and shaft, means for operatively connecting said shaft to a switch, a bearing for said shaft, a bushing around said shaft in said bearing, having a radial opening, and a hollow pin projecting into said opening and projecting outside said bearing.

22. In a switch-stand, a crank comprising a hub and an arm at the upper end of the hub when said hub is upright, said arm having a substantial bearing projecting down

substantially parallel with said hub, with a substantial bearing surface all around said projection.

23. In a switch-stand, a direct switch-throwing crank comprising an integral arm and hub, said hub having clutching means on one end, and having a threaded axial opening in said end.

FRANK C. ANDERSON.
